TOILET FLUSH CONTROL

Charles M. Goodwin, Rte. 2, Mount Vernon, Ohio
Filed Feb. 3, 1960, Ser. No. 6,390
7 Claims. (Cl. 4-67)

This invention relates to flush mechanisms for toilets and more particularly to both a conversion for existing flush mechanisms and a new flush mechanism to be used as original equipment.

An object of the invention is to provide a toilet flush control which provides the user with the option of obtaining a full flush or any portion thereof and without the use of any additional levers, controls, knobs, buttons, handles, or the equivalent.

The concept of providing for a partial flush is not new. However, prior constructions have always resulted in complications which outweighed the usefulness of the flush control mechanism. In all cases of which I am aware, an additional handle of some kind is required. First of all, this is an inconvenience and secondly, this usually means altering the china flush tank to make another hole in it. This is a serious difficulty since manufacturers are reluctant to introduce a new line of china tanks, and manually drilling a china tank is not an en- viable task.

Another difficulty in prior mechanisms for achieving partial flushes is in the operating mechanism itself. A flush mechanism cannot be made complex because the moving parts are subject to corrosive accumulations, and the nature of the outflow valve. It is difficult enough to maintain the outflow valve in proper adjustment so that it does not leak, with the simplest type of flush mechanism. When the operating parts are encumbered with too many mechanical linkages and parasitic working parts, the operation of the outflow valve becomes entirely too critical for long-lasting satisfactory service.

Briefly, a toilet flush control mechanism in accordance with the invention is embodied in a single additional stem slidably connected with the outflow valve stem, and an alteration in the connection between the conventional stem which attaches to the same outflow valve stem and the lift lever. The two stems, i.e., the stem provided by the invention and the stem ordinarily found in conventional flush mechanisms, are attached to the lift lever by a lost motion connection and a pair of stops. Apart from suitable guides, this is the structural nucleus of the flush control mechanism of the invention. In order to assure long and satisfactory service, a spring may be attached to the lever to function as a return spring, and a very handy place to connect this spring is to the lever and to the bushing nut at the pivot end of the lift lever or arm.

In view of the foregoing it is seen that commercial practicability and simplicity as well as great flexibility of flush quantity selection, are features of this invention.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is an elevational view of a flush tank, parts broken away to expose otherwise obscure details of construction, this figure showing the flush tank mechanism as it would appear prior to a typical operational use.

FIGURE 2 is a view similar to FIGURE 1 but showing the water being discharged from the tank and the mechanism in the proper position during the procedure.

FIGURE 3 is a view similar to FIGURE 1 but showing the flush mechanism being operated to select approximate-

2

ly one-half the water as the desired amount for the flush of the toilet.

FIGURE 4 is a sectional view on an enlarged scale taken on the line 4-4 of FIGURE 1.

5 FIGURE 5 is a sectional view on an enlarged scale taken on the line 5-5 of FIGURE 1.

FIGURE 6 is a sectional view taken on the line 6-6 of FIGURE 1 and on an enlarged scale.

10 FIGURE 7 is an enlarged sectional view taken on the line 7-7 of FIGURE 1.

In the accompanying drawings there is an illustration of a conventional china tank 10 with its lid 12 and a number of parts which are purely conventional and unaltered by the existence of the toilet flush control mechanism of the invention. These include overflow tube 14, outflow fitting comprising a seat 16, outflow ball valve 18, refill tube 20, float 22 and float arm 24. The lift lever or arm 26 is also conventional in construction and has a pivoted end 28 passed through an opening 30 in the wall of the 20 flush tank 10. The handle 32 for operating the lift arm or lever 26 is also conventional and attached to pivoted end 28 of lever 26. Stem 34 attached to outflow valve 18 is an ordinary stem equipped with an eye 36 at the upper end thereof. Ordinarily, stem or lift rod 38 is equipped 25 with a single eye at its lower end and is engaged in one of the openings 40 in the lift lever or arm 26 so that upon operation of handle 32, the lift lever 26 elevates stems 38 and 34. This commences the flush cycle of an ordinary flush tank mechanism. Since the above assembly is quite 30 common, no minute details are given.

The invention improves the operation of the flush mechanism by the inclusion of stem or push rod 39 which has a right angular lower end 42 equipped with an eye 44 through which stem 34 passes. Stem 38 is altered to the 35 extent that it has two eyes 46 and 48 at its lower end, and stems 34 and 39, respectively, pass through the eyes 46 and 48 (FIGURE 6). Guide 50 attached to overflow tube 14, is altered to the extent that it has two guide 40 passages 52 and 54, one passage for each of the stems 34 and 39, below eyes 46 and 48.

A support bracket 60 is secured to the lift lever or arm 26, for instance, by a small screw or screws 62. The support bracket 60 is required as a portion of a lost motion connection between stems 38 and 39. Therefore, the 45 bracket has a pair of spaced slots 66 formed therein, and the bracket is simply slipped over the end of lever 26 by having the lever enter and pass through the slots 66. A lateral shelf 67 of the bracket 60 is equipped with a pair of apertures through which stems 38 and 39 pass. There 50 are two adjustable stops 72 and 74 on stems 38 and 39, stop 72 being above flange 67, and stop 74 being below the same flange. Setscrews 73 secure the stops 72 and 74 on the stems 38 and 39.

There are resilient return means connected with lift 55 arm or lever 26. These means preferably, but not necessarily, consist of a leaf spring 78 (FIGURE 4) having one end 79 coupled to the pivot assembly for the pivoted inner end of lift lever 26. The opposite end of the spring has a saddle 80 formed therein which embraces the lower 60 part of the lift lever 26. The spring 78 is essentially U-shaped and the bias of the spring is in a direction tending to return the lift arm or lever 26 to the rest or original position.

65 In operation, handle 32 is actuated in the usual way. Notice that there is no alteration of tank 10 whatsoever and further, there are no additional manual controls, i.e., the controls in addition to the usual handle 32. When the handle is lifted, the lift lever 26 is elevated thereby 70 commencing the flush operation by elevating the stems 38 and 34, respectively. Stem 39 simply floats or idles as shown in FIGURE 2 during this procedure. If nothing

more were done the flush would be absolutely conventional.

However, should a person decide to reduce the quantity of the flush to any amount whatsoever, he would simply operate handle 32 in the opposite direction. This is depicted in FIGURE 3, and what happens is that the bracket 60 is moved downward until a part of it contacts stop 74 and this pushes stem 39 downward. The eye 44 on stem 39 physically pushes the outflow valve 18 down until it seats upon the outflow fitting 16, and this discontinues the flush. Thereafter, spring 78 will automatically return the lever 26 to its rest position. Notice that in the event that the outflow valve 18 does not seat properly, i.e., there is a slight leakage, all the person has to do is operate the handle 32 in a proper direction to cause the stem 39 to be depressed to the extent that the eye 44 thereof physically pushes the outflow valve 18 to a seated position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In a flush mechanism which has a lift lever and a stem and an outflow valve provided with a stem engaged with the first-mentioned stem, the improvement comprising a flush quantity control means which includes a third stem, means slidably connecting the third stem with the outflow valve stem, and lost motion connection means slidably attaching said first-mentioned stem and said third stem to one end portion of said lever for limited sliding movement, said lost motion connection means including a bracket connected with said lever and having apertures, said first and third stems passed through said apertures, and stops connected with said first and third stems respectively and adapted to be engaged by said bracket.

2. In a flush mechanism which has a lift lever and a stem and an outflow valve provided with a stem engaged with the first-mentioned stem, the improvement comprising a flush quantity control means which includes a third stem, means slidably connecting the third stem with the

outflow valve stem, and lost motion connection means slidably attaching said first mentioned stem and said third stem to one end portion of said lever for limited sliding movement, said lost motion connection means including a bracket connected with said lever and having apertures, said first and third stems passed through said apertures, and stops connected with said first and third stems respectively and adapted to be engaged by said bracket, means connected with said stops for adjustably positioning said stops on said first and third stems.

10 3. The subject matter of claim 2 wherein said adjustable positioning means include set screws.

4. The subject matter of claim 2 wherein there is a return spring connected with said lift lever to return said lift lever to a rest position.

15 5. The subject matter of claim 2 wherein said first stem has two eyes at the lower end thereof, said outflow valve stem passed through one of said eyes, and said third stem passed through the other of said eyes.

20 6. In a flush mechanism which has an outflow valve provided with a stem, and a first stem connected with said outflow valve stem for lifting said outflow valve, a flush control comprising a mechanical connection including a lever slidably connected at one end to the first stem to elevate said first stem, and means slidably connecting said

25 one end of said lever of said mechanical means and said outflow valve stem for physically returning said outflow valve in response to movement of said lever in one direction, said mechanical means including a bracket provided with apertures through which said first and third stems pass, and stops attached to said first and third stems and located on opposite sides of said bracket.

30 7. The subject matter of claim 6 wherein there is a return spring operatively connected with said lever to return said lever to a rest position.
